UNITED STATES PATENT OFFICE.

FREDERICK H. PERRY, OF BEVERLY, MASSACHUSETTS, ASSIGNOR TO UNITED SHOE MACHINERY COMPANY, OF PATERSON, NEW JERSEY, A CORPORATION OF NEW JERSEY.

WELT-BEATING MACHINE.

1,164,858.

Specification of Letters Patent. Patented Dec. 21, 1915.

Application filed December 26, 1911, Serial No. 667,624. Renewed March 16, 1915. Serial No. 14,770.

To all whom it may concern:

Be it known that I, FREDERICK H. PERRY, a citizen of the United States, residing at Beverly, in the county of Essex and State of Massachusetts, have invented certain new and useful Improvements in Welt-Beating Machines; and I do hereby declare the following to be a full, clear, and exact description of the invention, such as will enable others skilled in the art to which it appertains to make and use the same.

This invention relates to welt beating machines.

In the manufacture of welted shoes the welt after being attached to the upper and insole is subjected to a beating out operation in order to cause it to lie flat in substantially the plane of the insole. Since the inner and outer edges of the welt are equal in length, the outer portion of the welt is often drawn inwardly after the welt is attached to the insole, particularly about convexly curved portions of the sole such as the toe, causing a welt to warp or wrinkle. It is therefore necessary to stretch the outer edge of the welt considerably in order to cause all portions of the welt to lie in the plane of the insole. The tension exerted by the outer portion or edge of the welt during the beating operation, as heretofore performed, compresses the welt laterally and makes it narrower and thicker, especially at the portions of the shoe having a sharply convex curvature, thereby causing irregularities and unevenness in the completed work.

One object of the present invention is to produce a welt beating machine by which the welt may be beaten out flat in substantially the plane of the insole in a more rapid and efficient manner than could be done heretofore.

A further object is to produce a welt beating machine by which the welt may be stretched or extended in the direction of its width during the beating out operation so as to obviate the narrowing and thickening of the welt at curved portions of the sole.

With the above objects in view one feature of the invention contemplates the provision in a welt beating machine of one or more beating elements arranged to move into en-

gagement with the welt and thereafter to move over the welt in rubbing contact therewith and means constructed and arranged to cause the beating elements to move over the welt in a direction transverse to the welt.

A further feature of the invention contemplates the provision in a welt beating machine of a series of beating elements arranged to be brought into successive engagement with the welt and constructed to form indentations in the welt, and to smooth out the indentations, alternately. The indentations are preferably formed in series widthwise of the welt and in the best form of the invention which has yet been devised the faces of the welt beating elements are constructed to form widthwise of the welt series of corrugations extending longitudinally of the welt, or, in the general direction of its edges. By the alternate indenting and smoothing out of the welt, the wrinkles and irregularities are removed from the leather, the welt is stretched to a greater degree than heretofore so as to cause it to lie flat in the plane of the insole. By forming the indentations in series widthwise of the welt and thereafter smoothing out the indentations, the welt is extended or stretched particularly in the direction of its width thereby avoiding the thickening and narrowing of the welt at sharply curved portions of the shoe.

Further features of the invention consist of certain constructions, arrangements and combinations of parts, the advantages of which will be obvious to those skilled in the art from the following description.

In the drawings illustrating the invention in the best form at present known to the inventor,—Figure 1 is a side elevation of a welt beating machine embodying the invention, a portion thereof being shown in section; Fig. 2 is a plan of the machine with a portion of the upper casing removed to more clearly show the structure; Fig. 3 is a front elevation of the machine; Fig. 4 is a detail rear elevation of the rotary head with the beating elements attached thereto; Fig. 5 is a section taken on the line 5—5 of Fig. 4; Fig. 6 is a diagrammatic view of the series of beating elements illustrating the

formation and arrangement of the welt beating faces thereof; and Fig. 7 is a diagrammatic view of a series of beating elements the beating faces of which are modified in form and arrangement.

The machine illustrated in the drawings comprises a rotary head or carrier indicated at 1 on which is mounted a series of beating elements or hammers for beating out the welt. The head is mounted upon a shaft 2 journaled in a frame 3 which is supported by a table 4 formed on the base 5 of the machine, the said shaft being provided with the usual band wheel 6. The rotary head comprises a flanged disk 7 secured to the shaft 2 and a second flanged disk 8 secured to the disk 7. The beating elements or hammers indicated individually at 9 and 10 are pivoted between the flanges of the disks 7 and 8 upon pivot pins 11. These beating elements are provided with heavy heads remote from their pivotal points formed with welt beating faces for engagement with the welt. The said elements are pivoted at points eccentric to their masses so that upon rotating the head 1 the heads of the beating elements are thrown outwardly by centrifugal force carrying the welt beating faces of the heads beyond the peripheries of the disks 7 and 8. The outward or radial movement of the heads of the beating elements or hammers is limited by shoulders 12 formed on the sides of each element to engage annular flanges 13 and 14 formed respectively on the disks 7 and 8. By this arrangement the beating elements act in a direction oblique to the surface of the stock and deliver a sliding blow to the stock. The usual welt beating or flattening out action is primarily produced by the impact of the beating elements as they strike the work. On account of the large mass of the heads of the beating elements and the eccentric location of their pivotal points, the beating elements do not readily rebound from the surface of the work although they yield sufficiently to prevent injury to the work. After the first impact, the beating element continues its forward movement in contact with the welt. This movement exerts a pull on the welt as the beating element advances over its face.

The welt support for supporting the welt against the action of the beating elements is indicated at 15. This support comprises a welt supporting head 16 eccentrically mounted on a shank 17 and extending forwardly from the shank, the forward edge of the head being thinned to extend into the welt crease and support the welt close to the upper. The shank 17 is arranged to slide vertically in a bore 18 formed in the forwardly projecting portion 19 of the frame and with a threaded stem 20 upon the extremity of which is threaded an adjusting nut 21. A coil spring 22 surrounds the up-

per portion of said stem and engages at its extremities the shank 17 and a collar 23 surrounding said stem to yieldingly support the head 16. The collar 23 is exteriorly threaded and is adjusted vertically in the bore 18 by means of an adjusting nut 24 threaded on the collar and held in a slot in the portion 19 of the frame, the said collar being held from turning movement by pins 25 working in a groove in said collar. By manipulating the nuts 21 and 24 the height of the head 16 and the tension of the spring 22 may be adjusted as desired. The welt is supported on the surface of the head 16 and during the rotation of the rotary head the beaters are brought into engagement with the welt and deliver a series of sliding blows upon the same.

In Figs. 1, 2 and 3 the rotary head and the welt support are illustrated in their normal relative positions. When the shoe is supported in normal position on the welt support with the forward edge of the head of the support extending into the welt crease and the rotary head is in the position illustrated in Figs. 1, 2 and 3, the plane of rotation of the rotary head will be substantially parallel to the length of the portion of the welt on the welt support. Therefore the blows are delivered by the beating elements oblique to the surface of the welt and in the direction of its length at the point of operation, and the pull exerted by the beating elements acts to stretch the welt in the direction of its length and to assist in feeding the welt, assuming that the welt is advanced by the operator in the direction in which the beating elements move over it. It is desirable to stretch or extend certain portions of the welt widthwise, particularly those portions of welt extending about curved portions of the sole which tend to become narrowed and thickened during the beating operation. In the present invention provision is made for the adjustment of the beating elements to direct the blows delivered by said elements in directions transverse to the welt so that the drag or pull is exerted by the beating elements in directions transverse to or widthwise of the welt, thereby stretching the welt in the direction of its width. The beating elements are preferably arranged for adjustment to vary the angular direction of the blows delivered by the said elements with relation to the length of the welt so that the width extending action of the beating elements may be varied. In the present embodiment of the invention provision is made for the adjustment of the rotary head or carrier so that the plane of rotation thereof is oblique to the length of the welt, to direct the blows delivered by the beaters in directions transverse to the welt. In order to provide for this adjustment of the rotary head a depending arc-shaped

tongue 26 dovetail in cross section is formed on the frame 3 which supports the shaft 2, the center of the arc of said groove being taken in or adjacent to the surface of the 5 welt supporting head.

The table 4 upon which the frame 3 is supported is provided with a dovetail groove 27 curved to correspond with the curvature of the tongue 26 in which groove the said 10 tongue is received. The frame 3 may be adjusted in different angular positions to vary the angular position of the plane of rotation of the rotary head with relation to the length of the welt by sliding the frame 15 3 across the table 4, the said frame being guided in its movements by the tongue and groove connection between the frame and table. In order to adjust the frame on the table, a treadle operated mechanism is provided for moving the frame to different angular positions. Said mechanism comprises a shaft 28 journaled in the base below the frame and provided with a worm wheel 29 which meshes with a series of teeth 30 formed on a rack 31 secured to the frame 3. The shaft 28 is rotated by means of a gear segment 32 mounted on a rock shaft 33 and meshing with a pinion 34 carried by the 35 shaft 28. The rock shaft 33 is operated by suitable connections from treadles 34 and 35, said connections consisting of an arm 36 attached to the shaft 33 and connected with both treadles 34 and 35 by a link 37 and a pin 38 which passes through the extremity 40 of said link and engages both of said treadles. The treadle 34 is pivoted on a shaft 39 at a point between the pin 38 and the forward portion of the treadle to which the foot is applied. The treadle 35, on the 45 other hand, is pivoted on a shaft 40 at a point such that the pin 38 is located between said shaft and the forward portion of the treadle to which the foot is applied. By means of the treadles 34 and 35 and the 50 above described connections therefrom to the shaft 33 the frame 3 and the rotary head may be moved angularly in either direction to position the rotary head so that its plane of rotation is oblique to the length of the 55 welt and the head may be adjusted to rotate in a plane more or less oblique to the length of the welt as desired by varying the extent of depression of the treadle. The rock shaft 33 is held in a position to maintain the 60 frame 3 and the rotary head in its normal central position shown in Figs. 1, 2 and 3 by means of a plunger 41 mounted to slide in a guide in the frame and actuated by a coil spring 42. The head 43 of the plunger 65 engages a pair of rolls 44 attached to the rock shaft 33 and arranged so that the shaft is held by the engagement of the head of the plunger with the rolls in the central position shown in Fig. 1. Whenever during 70 the beating operation it is desired to stretch

the welt in the direction of its width the treadle 35 is depressed. By the depression of the treadle 35, the frame 3 is swung to the right (Fig. 2), so that the plane of rotation of the rotary head is oblique to the 75 length of the welt and the beating elements strike the welt in a direction transverse thereto and move obliquely across the welt from its inner to its outer edge. This operation of the beaters tends to draw the 80 shoe in toward the welt support and to maintain the bottom of the welt crease continuously against the edge of the welt support thereby assisting the operator in holding the shoe. By the transverse rubbing action of the beaters the welt is smoothed out transversely and stretched in a direction away from the upper to an extent depending on the angle at which the beaters move over the welt. The pull on the welt exerted by 85 the beaters also has the effect of drawing the inseam snugly down to the last bottom.

Ordinarily in adjusting the beaters so that they operate in a direction transverse to the welt it is desirable to cause the beaters to 90 move over the welt in a direction away from the upper. It often happens particularly when a light insole or one of inferior quality is employed that after the inseam is sewed irregularities appear at certain points there- 95 in due to the pulling of the leather along the seam away from the last during the sewing operation. It is therefore often desirable at certain portions of the welt to cause the beating elements to strike the welt trans- 100 versely and move over the same in a direc- 105 tion toward the upper so that the said ele- 110 ments will exert a rubbing action on the welt in a direction transverse thereto and toward the upper to bring the inseam back to its 115 proper position with relation to the last. In the illustrated embodiment of the invention this action may be secured by depressing the treadle 34 and thereby swinging the frame 3 to the left (Fig. 2) and locating the plane of 120 rotation in a position oblique to the length of the portion of the welt on the welt support. In this position of the rotary head the beating elements first engage the welt at its outer edge and move obliquely across 125 the welt toward the upper.

In order to relieve the tension on the outer portion of the welt particularly about the toe and other curved portions of the sole so that the welt may be beaten out properly, 130 it is necessary in some instances to slit or slash the welt at certain points so as to permit those portions of the welt in which the slashes are made to stretch or elongate. For this reason, in addition to the beating 135 elements for beating out the welt, welt slitting knives are secured to the periphery of the rotary head for slitting the welt in the manner to be hereinafter described.

In the illustrated embodiment of the in- 140

vention the welt slitting knives indicated at 45 are mounted on the heads of the diametrically opposed beating elements 10. To provide for mounting the knives thereon the 5 beating elements 10 are each constructed in two parts indicated at 46 and 47 (Fig. 5), said parts being formed with opposed recesses for the reception of the supporting shank or block 48 upon which the slitting 10 knife is mounted. The knife is held in the head of the beating element by a screw 49 which passes through a perforation in the part 47 and a registering perforation in the knife supporting block and is screwed into 15 the part 46. The block 48 is thereby clamped securely between the parts 46 and 47. The welt slitting knife is preferably arranged to project a distance beyond the welt beating face of the beating element such that it will 20 cut only partially through the welt. The welt is slashed by the welt slitting knives and beaten out by the welt beating faces of the knife carrying beaters simultaneously.

The heads of the beating elements 10 are 25 normally held withdrawn within the peripheries of the disks 7 and 8 so that the said beating elements and the welt slitting knives carried thereby are normally held out of operation. To maintain the heads of the 30 elements 10 normally withdrawn within the peripheries of the disks 7 and 8, rearwardly projecting lugs 50 are formed on the beating elements 10 which are engaged by forwardly projecting lugs 51 formed on an annular member 52 mounted to slide toward and 35 from the disk 7 on guide rods or bolts 53 secured in the said disk. The lugs 51 are provided with beveled faces 54 which are brought into engagement with beveled faces 40 55 on the lugs 50 upon forward movement of the member 52 and the heads of the beating elements 10 are thereby withdrawn within the peripheries of the disks. The heads of the said beating elements 10 are therefore 45 after held in withdrawn position by the engagement of the faces 56 of the lugs 50 with the faces 57 of the lugs 51.

The annular member 52 is moved toward and from the disk 7 to withdraw the beating 50 elements 10 from operation and to permit the said elements to be thrown into operation by the following mechanism. A pair of slides 58 are mounted in guides on opposite sides of the shaft 2 and are provided at 55 their forward extremities with rolls 59 which operate in a groove 60 formed in the periphery of the member 52. A transverse rock shaft 61 is mounted in the frame below the shaft 2 and a pair of arms 62 are attached to the said shaft and are connected at their respective extremities with the slides 58 by means of pins 63 passing through slots in the extremities of the arms 58 and secured to the slides. The rock shaft 61 is

operated by suitable connections from a 65 treadle 64, said connections consisting in the structure illustrated, of an arm 65 attached to said shaft and a rod 66 having a universal connection at one extremity with the arm 65 and at the other with the treadle. In order 70 to hold the beating elements 10 and the knives 45 normally withdrawn within the peripheries of the disks 7 and 8 a coil spring 67 is attached at one extremity to the arm 65 and at the other to an adjustable eye-bolt 75 68 mounted in a bracket 69. The said bolt is adjusted to vary the tension on the spring by adjusting the nut 70 threaded thereon.

When the welt is slashed or slitted in order 80 to relieve the tension on the outer portion thereof so that the welt may be beaten out in a satisfactory manner, it is desirable that the slits be made at an angle to the length of the welt in order that the outer portion of the welt may be permitted to stretch in the 85 direction of the length of the welt at the points at which the slashes are made. The treadles 64 and 35 are in adjacent positions so that both treadles may be depressed simultaneously to locate the plane of rotation 90 of the rotary head in a position oblique to the length of the welt and to operate the annular member 52 to permit the welt slitting knives to be thrown into operation. When the treadles 64 and 35 are depressed 95 the welt slitting knives are thrown into operation and on account of the oblique disposition of the rotary head with relation to the welt on the welt support, the slashes or slits made by the welt slitting knives will be 100 formed at an angle to the length of the welt.

Referring now to the diagrammatic illustration of the two series of beating elements in Figs. 6 and 7, in the series illustrated in Fig. 6 the beaters are indicated at *a*, *b*, *c*, *d*, *e* and *f*, of which the beaters *c* and *f* are knife carrying beaters and are therefore normally maintained out of operation. Of the remaining beaters in the series, the beaters *a* and *d* are provided with elevations on their welt engaging faces, these elevations preferably consisting of parallel ridges extending in a direction parallel with the plane of rotation of the beaters. Therefore, during 115 the rotation of the rotary head or carrier, inasmuch as the knife carrying beaters are maintained out of operation, the welt is subjected alternately to the action of the beaters provided with ridged and plane faces which operate to indent and smooth out the welt alternately. In the present embodiment of the invention the indentations are formed in series across or widthwise of the welt and consist of parallel grooves extending in the general direction of the length of the welt at 120 the point of operation. In the series of beaters illustrated in Fig. 7 consisting of beaters *a'*, *b'*, *c'*, *d'*, *e'* and *f'*, the beaters *c'* and *f'*

are knife carrying beaters and are therefore normally maintained out of operation. In this series, the beater a' is provided with a ridge upon the left hand portion of its acting face, the beater b' with a ridge at the middle portion of its acting face, the beater d' with a ridge at the right hand portion of its acting face, while the acting face of the beater e' is plane. The ridges upon the faces of the beaters a' , b' and d' extend in a direction parallel with the plane of rotation of the beaters and the series of beaters is arranged so that the ridge on the face of the beater a' is adjacent the forward portion of the rotary head. During the rotation of the rotary carrier, since the knife carrying apparatus are maintained out of operation, the welt will be alternately indented and smoothed out by the action of the beaters a' , b' , c' and the beater e' respectively. Each of the beaters a' , b' , and e' forms a groove in the surface of the welt and therefore the combined action of these beaters is to form across or widthwise of the welt a series of parallel grooves extending in the general direction of the length of the welt after which the welt is smoothed out by the smooth face of the beater e' . Therefore, as in the series of beaters illustrated in Fig. 6, the beaters a' , b' , d' and e' act to corrugate and smooth out the welt alternately. Each of the elevations on the welt beating faces of the beaters forms an indentation in the welt at the point at which it is brought into engagement with the same and the welt is thereby pressed out, made thinner and stretched at this point to a greater degree than could be done by a beater acting throughout the width of the welt. After a series of indentations are formed in the welt the indentations are smoothed out by the action of the smooth faced beater. By the successive indenting and smoothing out of the welt the welt is stretched to a greater degree than could be done in the ordinary beating operation as heretofore practised so that the outer edge of the welt is extended sufficiently to cause the welt to lie flat in the plane of the insole. By the formation of the series of indentations widthwise of the welt and the subsequent smoothing out of the same, the welt is stretched particularly in the direction of its width and the thickening and narrowing of the welt at the curved portions of the shoe is obviated. Owing to the arrangement of the beating elements a' , b' and d' , as illustrated in Fig. 7, the welt is indented progressively from its inner to its outer edge thereby stretching and smoothing the welt from its inner edge outwardly and extending the same in a direction away from the upper.

Although the invention as illustrated is embodied in a machine for beating out welts,

certain features thereof may be applied to other machines particularly to machines for pounding or beating out other portions of a shoe.

It is to be understood that the invention is not limited to the specific construction and arrangement of parts of the illustrated embodiment but that these constructions and arrangements may be changed and modified without departing from the broader features of the invention.

Having explained the nature and object of the invention and having specifically described one form of the mechanism in which it may be embodied, what is claimed is:

1. A welt beating machine having, in combination, a welt support, a series of beating elements arranged to be brought into successive engagement with the welt and constructed to form indentations in the welt and to smooth out the indentations alternately, and means to operate the beating elements.

2. A welt beating machine having, in combination, a welt support, and a series of beating elements arranged to be brought into successive engagement with the welt, certain of said elements being formed to indent the welt at one or more points widthwise of the same, and other of said elements being arranged to engage the welt throughout its width and formed to smooth out the indentations.

3. A welt beating machine having, in combination, a welt support, and a series of beating elements arranged to be brought into successive engagement with the welt and constructed to form indentations in the welt progressively and thereafter to smooth out the indentations.

4. A welt beating machine having, in combination, a welt support, and a series of beating elements arranged to be brought into successive engagement with the welt and constructed to form indentations in the welt progressively in the direction of its width and thereafter to smooth out the indentations.

5. A welt beating machine having, in combination, a welt support, and a series of beating elements arranged to be brought into successive engagement with the welt and formed to indent the welt progressively from its inner to its outer edge and thereafter to smooth out the indentations.

6. A welt beating machine having, in combination, a welt support, a series of beating elements having welt beating faces of different conformations arranged to be brought into successive engagement with the welt and means to operate the beating elements.

7. A welt beating machine having, in combination, a welt support, a series of beating elements having welt beating faces of different conformations in successive beaters ar-

- ranged to be brought into successive engagement with the welt and means to operate the beating elements.
8. A welt beating machine having, in combination, a welt support, a series of beating elements having welt beating faces of different conformations arranged to be brought into successive engagement with the welt and means to throw certain of said beaters out of operation.
9. A welt beating machine having, in combination, a welt support, a series of beating elements arranged to be brought into successive engagement with the welt and constructed to form corrugations in the welt and to smooth out the corrugations alternately and means to operate said beating elements.
10. A welt beating machine having, in combination, a welt support, a series of beating elements arranged to be brought into successive engagement with the welt and having welt beating faces constructed to form corrugations in the welt progressively in the direction of its width and thereafter to smooth out the corrugations and means to operate said beating elements.
11. A welt beating machine having, in combination, a welt support, a series of beating elements arranged to be brought into successive engagement with the welt and having welt beating faces constructed to form corrugations in the welt progressively from its inner to its outer edge and thereafter to smooth out the corrugations and means to operate said beating elements.
12. A welt beating machine having, in combination, a welt support, a rotary head, a series of welt beating hammers carried by said head, certain of said hammers having ridges formed on their welt beating faces in progressive arrangement in successive beaters and others of said hammers having smooth welt beating faces to corrugate the welt progressively and thereafter to smooth out the same.
13. A welt beating machine having, in combination, a welt support, a rotary head, and a series of welt beating hammers carried by said head, certain of said hammers having ridges formed on their welt beating faces in progressive arrangement from the front to the rear of said head in successive beaters and others of said hammers having smooth welt beating faces to corrugate the welt progressively from its inner to its outer edge and thereafter to smooth out the same.
14. A welt beating machine having, in combination, a welt support, a rotary head, a welt beater carried by said head and a welt slitting knife mounted to rotate with the head and arranged with its edge substantially parallel with the plane of rotation of the head.
15. A welt beating machine having, in combination, a welt support, a rotary head,
- a series of welt beating hammers carried by said head, welt slitting knives arranged with their edges substantially parallel with the plane of rotation of said head carried by said head, means to hold said knives normally out of operation and means to actuate said last named means to permit the knives to be thrown into operation.
16. A welt beating machine having, in combination, a welt support, a rotary head, a series of beaters carried by said head, welt slitting knives arranged with their edges substantially parallel with the plane of rotation of said head carried by said head, mechanism to maintain said knives normally out of operation, and manually operable means to actuate said mechanism to permit the knives to be thrown into operation, said mechanism acting to withdraw said knives from said operation upon the release of said manually operable means.
17. A welt beating machine having, in combination, a welt support, a rotary head, a series of beaters carried by said head, welt slitting knives carried by said head, supporting means for said knives having beveled faces formed thereon, mechanism for throwing said knives out of operation comprising a transversely movable member having beveled faces formed thereon for engagement with the beveled faces of said knife supporting means, and mechanism for moving said member to carry the beveled faces on said member and said knife supporting means out of engagement to permit said knives to be thrown into operation.
18. A welt beating machine having, in combination, a welt support, a rotary member, a series of beating elements carried by said member, said member having provision for adjustment to locate its plane of rotation in a position oblique to the length of the welt.
19. A welt beating machine having, in combination, a welt support, a rotary member, a series of beating elements carried by said member, said member having provision for adjustment to locate its plane of rotation in different angular positions with relation to the length of the welt.
20. A welt beating machine having, in combination, a welt support, a beater arranged to deliver blows on the welt in a direction oblique to its surface and having provision for rotary adjustment about an axis substantially perpendicular to the welt support and located adjacent to said support and means for operating the beater.
21. A welt beating machine having, in combination, a welt support, a beater arranged to deliver blows on the welt in a direction oblique to its surface, a frame supporting said beater, a base, and an arc shaped tongue and groove connection between said frame and said base, arranged

- to permit angular sliding adjustment of the frame with relation to the base to change the direction of movement of the beater with relation to the length of the welt.
22. A welt beating machine having, in combination, a welt support, a beater arranged to deliver blows on the welt in a direction oblique to its surface, a frame supporting said beater and having provision for angular adjustment in a plane parallel with the welt support, means for adjusting said frame comprising a toothed member secured to said frame, a worm meshing with the teeth of said member, a shaft supporting said worm, a gear on said shaft, a gear segment meshing with said gear, a rock shaft upon which said gear segment is mounted, and treadles and connections therefrom for rocking said last named shaft.
23. A welt beating machine having, in combination, a welt support, a rotary member, a series of beating elements carried by said member, welt slitting knives secured to said member, said member having provision for adjustment to locate its plane of rotation in a position oblique to the length of the welt, means for holding said welt slitting knives normally withdrawn from operation, and means under the control of the operator for actuating said last mentioned means to permit the knives to be thrown into operation and for adjusting said member to locate its plane of rotation in a position oblique to the length of the welt.
24. A welt beating machine having, in combination, a welt support, a welt beating element arranged to move into engagement with the welt and thereafter to move over the welt in rubbing contact therewith and a welt slitting knife mounted on the welt engaging portion of said welt beating element.
25. A welt beating machine, having, in combination, a welt support, a rotary head, and a welt slitting knife mounted on the head and arranged with its edge substantially parallel to the plane of rotation of the head, the head having provision for adjustment to locate its plane of rotation oblique to the length of the welt.
26. A welt beating machine having, in combination, a welt support, a rotary member, a series of welt beating elements eccentrically mounted on the rotary member, and welt slitting knives mounted on certain of the welt beating elements and arranged to project from the welt engaging faces thereof.
27. A welt beating machine having, in combination, a welt support, a beating element arranged to deliver blows on the welt in a direction oblique to its surface and means constructed and arranged to cause the beating element to strike the welt in a direction transverse thereto.
28. A welt beating machine having, in combination, a welt support, and a beating element arranged to deliver blows on the welt in a direction oblique to its surface and also arranged for adjustment to deliver blows in different angular directions with relation to the length of the welt.
29. A welt beating machine having, in combination, a welt support, a beating element arranged to move into engagement with the welt and thereafter to move over the welt in rubbing contact therewith and means constructed and arranged to cause the beating element to move over the welt in a direction transverse to the welt.
30. A welt beating machine having, in combination, a welt support, a beating element arranged to move into engagement with the welt and thereafter to move over the welt in rubbing contact therewith and means constructed and arranged to cause the beating element to move over the welt in a direction transverse thereto and away from the upper.
31. A welt beating machine having, in combination, a welt support, a beating element arranged to move into engagement with the welt and thereafter to move over the welt in rubbing contact therewith and means constructed and arranged to cause the beating element to move over the welt in a direction transverse thereto and toward the upper.
32. A welt beating machine having, in combination, a welt support, and a beating element having a movement downward on the welt and then along over the welt in rubbing contact therewith, said machine having provision for adjustment to direct the rubbing movement of the beating element transversely of the welt toward or away from the upper.
33. A welt beating machine, having, in combination, a support for the welt of a lasted shoe, and welt beating means arranged with relation to the welt support to beat out the portion of the welt supported thereby and constructed to form indentations in the welt and to smooth out the indentations.
34. A welt beating machine having, in combination, a welt support, beaters constructed and arranged to form indentations in the welt progressively in the direction of its width, and means for actuating the beaters.
35. A welt beating machine having, in combination, a welt support, beaters constructed and arranged to form indentations in the welt progressively from its inner to its outer edge, and means for actuating the beaters.
36. A welt beating machine having, in combination, a welt support, a welt beater having a blunt faced indentation forming projection on its welt engaging portion and

means for actuating the beater to cause it to move into engagement with the welt, and thereafter to move over the welt in rubbing contact therewith.

- 5 37. A welt beating machine having, in combination, a welt support, beaters constructed and arranged to form indentations in the welt at different points in the direc-

tion of its width, and means for actuating the beaters to cause them to engage the welt successively.
